Harry Jacobson
ATTORNEY

UNITED STATES PATENT OFFICE.

IRA I. BLOOM, OF NEW YORK, N. Y.

TOY.

1,258,862.

Specification of Letters Patent. Patented Mar. 12, 1918.

Application filed March 19, 1917. Serial No. 155,749.

To all whom it may concern:

Be it known that I, IRA I. BLOOM, a citizen of the United States, and resident of the city of New York, in the county of New York and State of New York, have invented certain new and useful Improvements in Toys, of which the following is a specification.

This invention relates to toys and toy submarines and especially to those which are 10 submerged by the addition of weights.

One of the objects of this invention is the provision of means for indicating the submerged position of the submerging weight.

Another object of this invention is the 15 provision of a weight adapted especially for use in connection with self raising submersible toys which automatically discharge the weight, and for retrieving the weight after it has been discharged from the toy.

20 Further objects will appear from the description and claims.

I accomplish these objects by the devices shown in their preferred forms in the accompanying drawings, in which—

25 Figure 1 is a front view and partial section of one form of toy submarine showing a weight adapted for use therewith.

Fig. 2 is a section of a portion of a self raising and automatic weight discharging 30 toy submarine showing a modified form of submerging weight.

Fig. 3 is a front view showing the position of the weight after it has been discharged from the toy shown in Fig. 2 and before it 35 has reached the bottom and Fig. 4 is a similar view of the weight resting on the bottom and showing the indicating float at the surface.

In the practical embodiment of my invention, the weight 3 is designed for use in the 40 type of toy submarine shown in Fig. 1 which has an opening 2 in the hull 1 extending part way through said hull. Float 4, such as a cork, water tight ball or similar buoyant object, is attached to weight 3 by some 45 flexible light connection such as a string 5, one end of said string being attached to the float at 7 and the other end of said string passing through a hole 6 in the base of said 50 weight. A knot as 9 prevents the string from being pulled back through the hole. Weight 3 is shown partly hollow for convenience in inserting float 4 very loosely 55 therein, though the weight may be solid if desired.

For the self raising form of toy shown in

Fig. 2, the opening 2 in hull 1 extends entirely through said hull, the weight resting on disk 10 of the bell crank lever pivoted at 12, and having weight 11 to balance the 60 weight which may be placed on disk 10. For this form of toy, I prefer to use a weight as 8, which is partly hollow and open at one end and which is so shaped that the center of gravity falls near the closed end thereof 65 so that when said weight is dropped or discharged into the water, it will always tend to assume an upright position. (Fig. 4.) Float 4 has the string 5 wound thereon and fits loosely into the opening in weight 8, one 70 end of said string being attached to float 4 and the other end passing through a small opening in the base of weight 8 and being knotted at 9 to prevent its being pulled through.

75 In the form of toy shown in Fig. 1, string 5 is wound around float 4, said float being then inserted in weight 3. When it is desired to submerge the toy, the weight, held with the open end up, and the float freely 80 inserted in said weight, are dropped into opening 2. Weight 3 is of suitable mass to overcome the buoyancy of the toy to cause said toy to sink. As soon as the toy is submerged sufficiently to allow the water to enter over the top of tube 13, thereby filling opening 2, float 4 rises to the surface as shown by the dotted lines in Fig. 1, string 5 uncoiling as the float rises. To cause the toy to rise, weight 3 is withdrawn by means of 85 float 4. It is obvious that the string may be held in the hand and the weight dropped to the bottom of opening 2 and withdrawn as frequently as desired without the use of the float thereby causing the toy to sink and rise 90 alternately; or ring weights designed to fit around the periscope or other parts may be employed in a similar manner.

95 In the form of toy shown in Fig. 2, string 5 is wound around float 4 in the manner described above, weight 8 being inserted into 100 opening 2 with the base uppermost and float 4 is loosely inserted in the opening in said weight so that float 4 is held on to disk 10 by said weight. The insertion of said weight 105 into opening 2 submerges the toy. When the end 11 of the bell crank lever touches the bottom of the water, said end is raised, moving the lever to the position shown by the dotted lines (Fig. 2) thereby discharging weight 8 and float 4 contained therein. 110 The center of gravity of weight 8 being

near the base thereof, said weight will tend to assume an upright position (Fig. 3) thereby releasing float 4 which will rise to the surface (Fig. 4), string 5 uncoiling as the 5 float rises. The discharge of weight 8 from the toy will cause said toy to rise to the surface. The weight may be retrieved by pulling up float 4, the position of said weight being indicated by the float.

10 Attention is called to various slight changes in the method of operating my device and in the formation and location of the weights which if made will not depart from the scope of my invention; such as 15 making weight 3 solid instead of hollow; placing float 4 flexibly attached to weight 3 near said weight instead of in it; holding the string in the hand while operating the type of boat shown in Fig. 1, eliminating opening 2 in said type and placing the weight 20 on the deck. In connection with the type of boat shown in Fig. 2, float 4 connected to weight 8 may be painted to represent a floating mine, and the toy may be called an automatic mine layer, the float being the mine 25 and the weight being the anchor therefor.

I do not desire to limit my invention to use in connection with toy submarines only, as it is obvious that my improved devices 30 may be used in connection with any other form of submersible toy as well.

What I claim is:

1. In combination with a weight discharging toy, means for submerging said toy, and 35 means arranged with said submerging means to operate only after the discharge of said submerging means from said toy for indicating the position of said submerging means after submersion.

40 2. Means for submerging a toy submarine and for enabling the retrieval of said means, comprising a weighty, partly hollow body having its center of gravity near the closed end thereof, a floatable body, and 45 flexible means for connecting said floatable body with said weighty body.

3. Means for submerging a toy and for 50 indicating the position and enabling retrieval of said means comprising a partly hollow weighty body, a floatable body adapted to be inserted into said weighty body and a flexible member for connecting said floatable body with said weighty body.

4. In combination with an automatic 55 weight discharging toy, a weight for submerging said toy and means for retrieving said weight after said weight has been discharged from said toy, said retrieving means being arranged to be held down by said 60 weight until after the discharge of said weight from said toy.

5. In combination with an automatic 65 weight discharging toy submarine, means

for submerging said toy and for enabling the retrieval of said submerging means, comprising a partly hollow weight open at one end and having its center of gravity near the closed end thereof and a float flexibly connected to said body inserted in said weight, and means for automatically discharging said weight and float from said toy for causing said toy to rise to the surface and for causing said weight to rest on the bottom with the open end up, whereby said float is released and rises to the surface for 75 enabling the retrieval of said weight.

6. In combination with a weight discharging toy submarine, means for submerging said toy, means for discharging said submerging means, flexible means attached at 80 one end thereof to said submerging means and means attached to the other end of said flexible means adapted to automatically draw said other end of said flexible means to the surface after the discharge of said submerging means and not before said discharge.

7. In combination with a weight discharging toy submarine having an opening therein, a weight for insertion into said opening 90 for submerging said toy and a float flexibly connected to said weight arranged to be held down by said weight until said weight is discharged from said toy, and then to rise to the surface for indicating the position of 95 said weight and said toy.

8. In combination with an automatic weight discharging toy submarine, a weight for submerging said toy and a float flexibly connected to said weight adapted to rise to 100 the surface only after the discharge of said weight and float for indicating the position of said weights and for withdrawing said weight.

9. In combination with a toy submarine 105 having an opening therethrough, a weight adapted to be dropped into said opening, hinged means closing the lower end of said opening for holding said weight thereon and for automatically discharging said 110 weight when said toy reaches the bottom of the water, and a float flexibly connected to said weight adapted to rise to the surface on the discharge of said weight.

10. A partly hollow toy sinking weight 115 having its center of gravity near one end thereof and having a hole in the heavier end, a cork, and a string fastened to said cork and passing through said hole, said string being knotted to prevent its being 120 pulled back through said hole.

Signed at the city of New York, in the county of New York and State of New York, this 17th day of March, A. D. 1917.

IRA I. BLOOM.
